UNITED STATES PATENT OFFICE.

HUGO L. MUMM, OF WAUSAU, WISCONSIN.

PAPER-ROLL BUSHING.

1,408,126.

Specification of Letters Patent.

Patented Feb. 28, 1922.

Application filed July 28, 1920. Serial No. 399,471.

To all whom it may concern:

Be it known that I, HUGO L. MUMM, citizen of the United States, residing at Wausau, in the county of Marathon and State 5 of Wisconsin, have invented certain new and useful Improvements in Paper-Roll Bushings, of which the following is a specification.

This invention relates to improvements in 10 bushings or chucks especially adapted for use in supporting paper rolls.

An important object of this invention is to provide a chuck or bushing having an annular enlargement intermediate its ends 15 which serves to retain the chuck or bushing in the centrally arranged opening in a roll of paper so that the chuck or bushing will not be accidentally lost during handling or transportation of the roll of paper.

20 A further object of the invention is to provide a chuck or bushing for paper rolls which is simple to apply, efficient in use and cheap to manufacture.

Other objects and advantages of the invention will be apparent during the course 25 of the following description.

In the accompanying drawing forming a part of this application and in which like numerals are employed to designate like 30 parts throughout the same,—

Figure 1 is a central longitudinal sectional view through a paper roll having a pair of the improved bushings applied thereto,

Fig. 2 is a side elevation of a slightly 35 modified form of the invention,

Fig. 3 is a similar view of a further modification of the invention,

Fig. 4 is a similar view of a still further modification of the invention,

40 Fig. 5 is a similar view of another form of the invention,

Fig. 6 is an end elevation of the chuck illustrated in Fig. 1,

Fig. 7 is a side elevation of a further 45 modification of the invention.

In the drawing wherein for the purpose of illustration is shown a preferred embodiment of the invention, the numeral 5 generally designates a roll of paper which may 50 be wrapping paper, writing paper, print paper, paper used in building construction, or in fact any kind of paper. As illustrated in Fig. 1, the roll of paper 5 is provided with a centrally arranged longitudinally extending cylindrical opening 6 with-

in which a pair of bushings 8 are adapted to be arranged so that the roll of paper may be rotatably supported. The bushings are provided with longitudinally extending openings or bores 10 which rotatably receive 60 shafts or pivot pins 12 supported in any suitable manner. The bushing illustrated in Fig. 1 is of a tapered formation and is provided intermediate its ends with a rounded annular shoulder 14 which, when the 65 bushing is driven into the opening 6, firmly engages the inner wall of the opening 6 and thereby prevents the accidental displacement of the bushing. It will be observed that the shoulder 14 engages the paper roll 70 at a point spaced from the end of the same so that the paper outwardly of the rounded annular shoulder 14 may move inwardly and thereby lock the bushing 8 in position. A head 16 formed integral with the bushing 75 8 extends from one end of the same and is of a lesser diameter than the bushing so that the layers of paper may move inwardly to a slight extent for locking the bushing in position.

80 In the form of the invention illustrated in Fig. 2, the bushing 18 is in the form of a truncated cone and is formed adjacent its rear end with an annular shoulder 20 which is somewhat sharp. The bushing 85 extends inwardly rearwardly of the shoulder 20 and is formed with an extension 22 which allows the layers of paper to move inwardly upon the insertion of the bushing 18 into the opening 6. The shoulder 20, 90 which may be said to be V-shaped in cross section, engages the inner wall of the opening 6 so that the accidental displacement of the bushing is prevented.

95 As illustrated in Fig. 3, the bushing designated by the numeral 24 may be formed with an annular groove 26 rearwardly of an annular shoulder 28 similar to the annular shoulder 20. The groove 26 formed in the bushing provides a second annular shoulder 29 rearwardly of the shoulder 28 and of a greater diameter than the shoulder 28. In the use of this form of the invention, a portion of the paper is of course received in the annular groove 28 and the 100 annular shoulders 28 and 29 are therefore firmly engaged with the paper so that the accidental displacement of the bushing is prevented. Rearwardly of the shoulder 29, the bushing 24 is extended inwardly so as to 110

allow the layers of paper to move inwardly and thereby lock the bushing against displacement.

In the form of the invention illustrated in Fig. 4, the bushing 30 which is in the form of a truncated cone is formed adjacent its rear end with an annular groove 32. The annular groove 32 which is V-shaped in cross section forms a shoulder 33 and a second shoulder 34 having a diameter greater than the shoulder 33. In this form of the invention, the body of the bushing is also extended inwardly rearwardly of the groove so that the layers of paper may move inwardly upon the insertion of the bushing into the opening 6.

With reference to Fig. 5, it will be observed that the bushing designated by the numeral 36 is enlarged adjacent its rear end for forming an annular shoulder 38 which has a flat bearing surface adapted to engage the inner wall of the opening 6 so as to firmly hold the bushing in position.

A further modification of the invention is illustrated in Fig. 7 wherein the bushing indicated by the numeral 39 is provided adjacent its rear end with an annular groove 40 which may be said to be V-shaped in cross section. The groove 40 forms annular shoulders 42 and 44, the annular shoulder 44 being arranged rearwardly of the annular shoulder 42 and being of a lesser diameter than the first mentioned shoulder. This form of the invention is, like the form of the invention illustrated in Fig. 1, provided with an extension 46 which is of a lesser diameter than the annular shoulders

42 and 43 so that the layers of paper may move inwardly and thereby prevent the accidental removal or displacement of the bushing.

The inventive idea herein disclosed is capable of additional mechanical expressions and it is to be understood that the forms of the invention herewith shown and described are merely to be taken as preferred examples of the same.

Having thus described the invention, what is claimed as new is:

1. A bushing for rolls of paper consisting of a plug to be inserted in the axial opening through the roll with the outer end of the plug substantially flush with the end of the roll, the plug being provided with an external annular shoulder spaced inwardly from its outer end and the diameter of the outer end of the plug being less than the diameter of the plug at the shoulder whereby the edges of the inner plies of the roll may engage around the annular shoulder and retain the plug in place.

2. A bushing for rolls of paper consisting of plugs to be inserted in the axial opening through the roll with the outer end of the plug substantially flush with the end of the roll, the plug being tapered toward both ends and having its greatest diameter adjacent its outer end whereby the edges of the inner plies of the roll may engage around the outer tapered surface of the plug and retain the plug in place.

In testimony whereof I affix my signature.

HUGO L. MUMM. [L. s.]
